LASTING MACHINE

Theodore P. Courchene, Beverly, Mass., assignor
to United Shoe Machinery Corporation, Flem-
ington, N. J., a corporation of New Jersey

Application August 3, 1942, Serial No. 453,310

12 Claims. (Cl. 12—12)

This invention relates to lasting machines, and is herein illustrated as applied to a machine of the same general character as disclosed in United States Letters Patent No. 1,843,232, granted on February 2, 1932 on an application of B. Jorgensen's, but modified in certain respects as further disclosed mainly in Letters Patent No. 2,026,539, granted on January 7, 1936 also on an application of B. Jorgensen's. It is to be understood, however, that the invention is not limited to the particular embodiment illustrated.

A machine of the above-mentioned type is a power-operated machine which includes in its organization heel-lasting means mounted for preliminary positioning movement lengthwise of a shoe in the machine toward the heel end thereof from an initial retracted position in which it is held by a latch. This movement is effected by a spring upon release of the heel-lasting means by the operator prior to the starting of the power operation of the machine, and it is normally limited independently of the shoe by means provided for that purpose. To guard against possible injury to an operator or breakage of the machine, mechanism is further provided for preventing the starting of the machine unless the heel-lasting means has thus been released and has been moved toward the shoe. This mechanism comprises a device for locking the starting means against operative movement when the heel-lasting means is in its initial retracted position and for unlocking it in response to the movement of the heel-lasting means toward the shoe. The unlocking of the starting means has thus taken place heretofore prior to the substantial completion of that movement of the heel-lasting means by reason of the release by the latter of a lever which it engages in its retracted position to render the locking device operative.

An object of this invention is to afford still better insurance against breakage of such a machine under abnormal conditions. A machine of this type is often used to last tennis shoes or the like which are made on metal lasts each having in its heel end a pair of spindle holes spaced apart lengthwise of the last; and if such a shoe and its last are incorrectly presented by the operator with the usual last pin or spindle of the machine in the wrong spindle hole, the heel-lasting means, when released by the operator, may be prevented by the shoe and last from arriving at the normal limit of its positioning movement. This may happen also, regardless of the kind of last, if the last pin is badly displaced from its proper adjusted position. Under such conditions,

by reason especially of the character of the mechanism provided for operating the heel-lasting means, there is danger of breakage of some part of the machine in the power operation thereof. The present invention accordingly provides means for preventing the starting of the machine unless the heel-lasting means has received substantially its full normal positioning movement, or has arrived substantially at the normal limit of such movement. In the construction shown the above-mentioned device for locking the starting means against operative movement is rendered inoperative only by the very last portion of the normal positioning movement of the heel-lasting means. For this purpose the previously mentioned lever engaged by the heel-lasting means in its retracted position is held by a latch in position to prevent the starting of the machine until the heel-lasting means has nearly completed its normal positioning movement, whereupon the latch is operated to release the lever and thus to permit the starting of the machine.

The invention will now be more particularly described with reference to the accompanying drawings and thereafter pointed out in the claims.

In the drawings,

Fig. 1 is a view in front elevation of the upper right-hand portion of a machine of the type disclosed in the previously mentioned Letters Patent, as modified for purposes of the present invention, the parts being shown in the positions which they occupy after the release of the heel-lasting means and its movement toward the shoe;

Fig. 2 shows partly in plan and partly in section, on a larger scale, the lower portion of the structure shown in Fig. 1, with certain parts omitted;

Fig. 3 is a view of the lower portion of the machine in left-hand side elevation, showing mechanism controlled by parts shown in Fig. 1 for locking and releasing the starting means;

Fig. 4 is a view in front elevation, showing parts provided by the present invention for controlling the starting means, the parts being shown in the positions which they occupy prior to the release of the heel-lasting means; and

Fig. 5 is a view of a portion of the structure shown in Fig. 4, partly in right-hand side elevation and partly in section on the line V—V of Fig. 4.

In view of the disclosures of the previously mentioned Letters Patent, the present description

will be confined to such portions of the machine as it is necessary to refer to for an understanding of the invention. The shoe and its last are mounted on a last pin 2 which enters the usual spindle hole in the heel end of the last and is supported by a slide 4 movable vertically downward against the resistance of a spring 6 by pressure applied to the bottom of the shoe at a predetermined time in the power operation of the machine. The last pin is more directly supported, and is adjustable in directions heightwise of the shoe relatively to the slide 4, by means including a threaded vertical rod 8 carried by a slide 10 which is movable in directions lengthwise of the shoe along guideways on the upper end of the 15 slide 4 for a purpose hereinafter described.

For lasting the heel end of the shoe, the machine is provided with heel-lasting means including wipers 12 for wiping the margin of the upper inwardly over an insole on the last, a heel band 14 which serves as an abutment for engaging the heel-end face of the shoe and assists in conforming the upper to the contour of the last, and a carriage 16 supporting the wipers and the heel band. The carriage 16 is guided for movements 20 in directions lengthwise of the shoe on a pair of horizontal rods 18 (Figs. 1 and 2) which are fast on the vertically movable slide 4, the construction accordingly being such that the heel-lasting means accompanies the shoe in its downward 25 movement with the slide 4. To provide room for mounting the shoe on the last pin 2 the carriage 16 is held initially in an idle retracted position comparatively remote from the last pin by a latch 20 in engagement with a lug 22 on the lower end of the carriage, and upon its release by the latch 20 the carriage is moved toward the shoe by a spring 24 abutting against a bracket 25 fast on the outer 30 ends of the rods 18. The latch 20 is carried by an arm 26 which, through a rod 28, is moved downwardly by the operator as heretofore to release the carriage 16 to the action of the spring 24 after a shoe has been placed on the last pin. The normal limit of such movement of the carriage is determined by its engagement with stop washers 30 (Fig. 2) which are mounted on the rods 18 between the carriage and the slide 4.

As disclosed particularly in Letters Patent No. 2,026,539, the previously mentioned shoe support slide 10 is connected to another slide 32 (Fig. 2) also movable in directions lengthwise of the shoe along a guideway on a bracket 34 fast on the vertically movable slide 4. For thus connecting the two slides 10 and 32 there is provided a shaft 36 which is threaded in a nut 38 mounted in a recess in the slide 10 and is rotatable in a lug 40 formed on the slide 32. The shaft 36 is held from moving lengthwise relatively to the slide 32 by a collar 42 mounted on the shaft at one side of the lug 40 and a bevel gear 44 mounted on the shaft at the other side of the lug. The bevel gear 44 is engaged by another bevel gear 46 fast on a shaft 50 rotatable in the slide 32, on which shaft there is a hand wheel 52 for turning it. Accordingly, by means of this hand wheel the slide 10 may be moved relatively to the slide 32 to adjust the last pin 2 in directions lengthwise of the shoe as may be required for shoes of different sizes. Pivottally connected to the slide 32 is a link 54, and mounted between a nut 56 on the link and a plate 58 fast on the bracket 34 is a compression spring 60 which tends to move the two slides 10 and 32 as a unit toward the right as the parts are viewed in Fig. 1. Initially, however, the two slides are held somewhat farther toward

the left than shown in Fig. 1, against the resistance of the spring 60, by a latch 62 which is pivoted on the bracket 34 and controlled by a spring 64, the latch being arranged to engage a plate 65 on the slide 32. Accordingly, when the carriage 16 is held by the latch 20 in its initial retracted position toward the right, the slide 10 which carries the last pin 2 is held in a retracted position toward the left by the latch 62. When the carriage 16 is released by the operator and is moved by the spring 24 toward the shoe, the slide 10 is still held in its retracted position until the carriage 16 nears the end of its movement, whereupon a screw 68 on the lower end of the carriage engages the latch 62 and causes it to release the slide 10. The spring 60 then serves to move the slide 10 toward the right and thus to carry the shoe toward the heel band 14.

The link 54 is pivotally connected at its right-hand end to an arm 70 which is connected by gear teeth to another arm 72 movable to return the slide 10, after the lasting operations, to the position in which it is held by the latch 62. In the construction herein shown the arm 72 is thus operated by mechanism such as disclosed in Letters Patent No. 2,101,069, granted on December 7, 1937 on an application of B. Jorgensen's. This mechanism comprises a bar 74 which corresponds to the bar 346 shown in the last-mentioned Letters Patent and which by upward movement serves to swing the arm 72 in a counterclockwise direction (Fig. 1) and thus to impart the return movement to the slide 10. As fully disclosed in the last-mentioned Letters Patent, such upward movement of the bar 74 takes place in time relation to the operation of a shoe-removing device 76 with which the machine is provided after the shoe has been removed from the last pin 2 by this device, the carriage 16 having already been retracted to the position in which it is held by the latch 20 by automatic means acting through a chain 78 connected to the carriage.

As fully disclosed in the previously mentioned Letters Patent No. 1,843,232, the machine is operated through a clutch herein identified generally by the reference character 80 (Fig. 3). The clutch is controlled through a pin 82 having an enlarged head 84 arranged to be engaged by a plate 86 which is fast on an arm 88 mounted for upward and downward swinging movements. When the parts are positioned as shown in Fig. 3 the machine is idle, and to start it in operation it is necessary to swing the arm 88 upwardly and thereby to cause the plate 86 to release the pin 82. The arm is thus operated through a hook 90 in engagement with a plate 92 fast on the arm, the hook being mounted on the lower end of a link 94 which is moved upwardly by the swinging of a presser foot arm (not herein shown) to a position over the toe end of the shoe. To permit the machine to be stopped at the end of the cycle of operations by engagement of the plate 86 with the head 84 of the pin 82, the hook 90 is disconnected from the plate 92 shortly after the starting of the machine by a block 96 carried by the clutch. The arm 88 is then returned to its initial position by a spring 98 connected to another arm 100 which is mounted to swing with the arm 88 in fixed relation thereto.

As a measure of safety, the machine is further provided as heretofore with means for preventing the starting thereof when the carriage 16 of the heel-lasting means is held by the latch 20 in its initial retracted position. For this purpose a hook 102 formed on one end of a lever 104 piv-

oted at 100 on a bracket 108 at the base of the machine is arranged to engage a pin 110 on the lower end of a lever 112 which is connected at its upper end by a link 114 to the arm 100. As will be evident, when the hook 102 is in its operative position it serves by engagement with the pin 110 to prevent such upward movement of the arm 88 as to start the machine. To maintain the hook in that position when the carriage 16 is retracted, there is pivotally mounted on the bracket 25 (Figs. 1 and 4) a bell-crank lever 116 having a depending arm 118 engaged by the carriage 16 and another arm 120 connected by a link 122 to one arm of a bell-crank lever 124 (Fig. 1) at the base of the machine. The other arm of this bell-crank lever is connected by a link 126 to a depending arm 128 (Fig. 3) mounted to swing about a horizontal axis on the bracket 108. Integral with the hub of the arm 128 is a short arm 130 underlying the forward end of the lever 104. Interposed between the arm 130 and a screw 132 on the forward end of the lever 104 is a pivotally mounted arm 134 provided for a purpose which need not be herein explained but which is disclosed in Letters Patent No. 1,843,232. It is sufficient herein to note that by upward movement of the arm 130 acts through the arm 134 to raise the forward end of the lever 104 and thus to move the hook 102 downwardly into position to engage the pin 110. Such upward movement of the arm 130 results from movement of the bell-crank lever 116 in a counterclockwise direction in response to engagement of the carriage 16 with the arm 118 when the carriage is moved to its retracted position. When permitted by the bell-crank lever 116, a spring 136 connected to the hook 102 raises the hook into position to clear the pin 110, so that the machine may be thereafter started by upward movement of the arm 88. That is the position in which the hook is shown in Fig. 3, the carriage 16 in Fig. 1 having been released and moved toward the shoe.

It will be evident that the above-described safety mechanism effectively prevents the starting of the machine when the carriage 16 is in its initial retracted position. Heretofore the bell-crank lever 116 has been controlled wholly by the engagement of the carriage 16 with the arm 118 of the lever, and accordingly as the carriage has started to move toward the shoe the hook 102 has started to move upwardly toward its inoperative position by reason of the progressive release of the lever 116. The hook, therefore, has arrived in position to permit the starting of the machine when the carriage has been still a substantial distance short of the normal limit of its movement determined by its engagement with the washers 30. This has been entirely satisfactory under most conditions, i. e., when conditions have been such as to permit the carriage to receive its full positioning movement. Occasionally, however, the position of a shoe is such that the carriage is stopped short of the normal limit of its positioning movement by reason of the engagement of the heel band 14 with the shoe. This may be due to the fact that in the use of a metal last having two spindle holes the last pin 2 is positioned in the wrong spindle hole, or to the fact that the last pin has been badly displaced from its proper position by the hand wheel 53. If the machine is operated under these conditions there is danger of breakage of parts, as will be understood from a consideration of the character of the mechanism whereby the heel wipers 12 are operated. The construction of this

mechanism is more fully disclosed in Letters Patent No. 1,979,269, granted on November 6, 1934, on an application of B. Jorgensen's. Briefly, the wipers are advanced and closed, after their downward movement with the shoe, by movement lengthwise of the shoe of a plunger 138 supported by the carriage 16, and the plunger is operated by a bell-crank lever 140 which is supported independently of the carriage and has a movement of fixed extent, the lever having a plate 142 which engages a roll 144 on the end of the plunger 138. It will be evident that any substantial variation in the position of the carriage 16 at the end of its positioning movement lengthwise of the shoe affects substantially the relation of the plunger 138 to the bell-crank lever 140.

In view of the above and other considerations, the construction herein shown is such that starting of the machine is prevented unless the carriage 16 has arrived substantially at the normal limit of its movement determined by the washers 30. Pivotally connected at one end to the arm 118 of the bell-crank lever 116 is an arm 146 the other end of which is supported in a slot 148 (Fig. 5) of a bracket 150 fast on the vertically movable shoe support slide 4. This arm serves as a latch to prevent movement of the bell-crank lever 116 as the carriage 16 begins its movement toward the shoe, and for this purpose is provided with a shoulder 152 (Fig. 1) which engages a vertical face 153 on the bracket 150 when the parts are positioned as shown in Fig. 4. A spring 154 tends to swing the arm 146 downwardly and thus to maintain it in operative position. Pivotally mounted on a pin 156 on the bracket 150 is a bell-crank lever 158 having a depending arm 160 provided with a screw 162 arranged to be engaged by a face 164 (Fig. 2) on the carriage 16 when the carriage has nearly arrived at the normal limit of its positioning movement. The bell-crank lever 158 has also a substantially horizontal arm 166 provided with a screw 168 arranged to engage the lower face of the arm 146. Accordingly, the carriage 16 acts through this bell-crank lever to swing the arm 146 upwardly and thus to release the bell-crank lever 116. Such release of the lever 116, however, occurs only when the carriage has substantially arrived in the position determined by the washers 30, the screws 162 and 168 being adjustable to secure a high degree of precision in this respect. If, therefore, under abnormal conditions such, for example, as hereinbefore described, the carriage 16 fails to receive substantially its full normal positioning movement, the starting of the machine is still prevented by the hook 102 (Fig. 3) and danger of breakage of the machine under those conditions is avoided. It will be understood that in response to each return movement of the carriage 16 to the position in which it is held by the latch 20 the latch arm 146 is returned to the operative position in which it is shown in Fig. 4.

The manner of operation of the construction provided for purposes of this invention having been fully explained above, no further description of the operation is necessary.

Having described the invention, what I claim as new and desire to secure by Letters Patent of the United States is:

1. In a power-operated lasting machine, the combination with a shoe support, of lasting means having a normal range of movement from an initial retracted position into position for operating on a shoe on said support, means for starting the power operation of the machine, and mech-

anism for preventing the starting of the machine by said starting means unless said lasting means has received substantially the full positioning movement thus provided for.

2. In a power-operated lasting machine, the combination with a shoe support, of lasting means movable from an initial retracted position into position for operating on a shoe on said support, means for normally limiting independently of the shoe such movement of the lasting means, means for starting the power operation of the machine, and mechanism for preventing the starting of the machine by said starting means unless said lasting means has been moved from its initial retracted position substantially to the position determined by said limiting means.

3. In a power-operated lasting machine, the combination with a shoe support, of lasting means movable from an initial retracted position into position for operating on a shoe on said support, a spring for thus moving said lasting means, stop mechanism for normally limiting the movement thereof, means for starting the power operation of the machine, and mechanism for preventing the starting of the machine by said starting means unless said lasting means has been moved by said spring substantially to the position determined by said stop mechanism.

4. In a power-operated lasting machine, the combination with a shoe support, of lasting means movable from an initial retracted position into position for operating on a shoe on said support, means for normally limiting independently of the shoe such movement of the lasting means, means for starting the power operation of the machine, a device for rendering the starting means inoperative when the lasting means is in its retracted position, and mechanism controlled by the positioning movement of the lasting means for rendering said device inoperative to prevent the starting of the machine only when the lasting means has arrived substantially in the position determined by said limiting means.

5. In a power-operated lasting machine, the combination with a shoe support, of lasting means movable from an initial retracted position into position for operating on a shoe on said support, means for normally limiting independently of the shoe such movement of the lasting means, means for starting the power operation of the machine, a device for locking the starting means against movement to start the machine when the lasting means is in its retracted position, and means to cause said device to unlock the starting means in response to the positioning movement of the lasting means only when the lasting means has arrived substantially in the position determined by said limiting means.

6. In a power-operated lasting machine, the combination with a shoe support, of heel-lasting means mounted for preliminary positioning movement lengthwise of a shoe on said support from an initial retracted position, means for determining independently of the shoe a normal limit of such movement of the lasting means, power-operated mechanism independently of which the lasting means is thus movable for thereafter operating said lasting means, means for starting the power operation of the machine, and mechanism controlled by said lasting means for preventing the starting of the machine unless the lasting means has arrived substantially at the normal limit of its positioning movement.

7. In a power-operated lasting machine, the

combination with a shoe support, of heel-lasting means mounted for preliminary positioning movement toward the heel end of a shoe on said support from an initial retracted position, means for determining independently of the shoe a normal limit of such movement of the lasting means, means for starting the power operation of the machine, mechanism including a member arranged to be operated by movement of the lasting means to said retracted position for preventing the starting of the machine when the lasting means is in that position, and means for retaining said member still in position to prevent the starting of the machine as the lasting means begins its positioning movement toward the shoe, said retaining means being movable to release said member in response to the positioning movement of the lasting means only when the lasting means has arrived substantially at the normal limit of said movement.

8. In a power-operated lasting machine, the combination with a shoe support, of heel-lasting means mounted for preliminary positioning movement toward the heel end of a shoe on said support from an initial retracted position, means for starting the power operation of the machine, mechanism including a member arranged to be operated by movement of the lasting means to said retracted position for preventing the starting of the machine when the lasting means is in that position, a device for retaining said member still in position to prevent the starting of the machine as the lasting means begins its positioning movement toward the shoe, and means for thereafter operating said device to release said member in response to the positioning movement of the lasting means near the end of said movement.

9. In a power-operated lasting machine, the combination with a shoe support, of heel-lasting means mounted for preliminary positioning movement toward the heel end of a shoe on said support from an initial retracted position, means for starting the power operation of the machine, mechanism including a member arranged to be operated by movement of the lasting means to said retracted position for preventing the starting of the machine when the lasting means is in that position, a latch for retaining said member still in position to prevent the starting of the machine as the lasting means begins its positioning movement toward the shoe, and a lever movable thereafter by the lasting means to operate said latch and thereby to release said member as the lasting means nears the end of its positioning movement.

10. In a power-operated lasting machine, the combination with a shoe support, of an abutment for engaging the heel-end face of a shoe on said support, a carriage supporting said abutment and movable lengthwise of the shoe to carry the abutment into shoe-engaging position prior to the starting of the power operation of the machine, means for normally limiting such movement of the carriage, means for starting the power operation of the machine, and mechanism for preventing the starting of the machine by said starting means if the carriage is prevented by engagement of the shoe with said abutment from arriving substantially in the position determined by said limiting means.

11. In a power-operated lasting machine, the combination with a shoe support, of an abutment for engaging the heel-end face of a shoe on said support, a carriage supporting said abutment and

movable lengthwise of the shoe from an initial retracted position to carry the abutment into shoe-engaging position prior to the starting of the power operation of the machine, means for normally limiting such movement of the carriage, means for starting the power operation of the machine, mechanism controlled by said carriage for preventing the starting of the machine by said starting means when the carriage is in its initial retracted position, and a device for retaining said mechanism still in position to prevent the starting of the machine if the carriage is prevented by engagement of the shoe with said abutment from arriving substantially in the position determined by said limiting means.

12. In a power-operated lasting machine, the combination with a shoe support, of an abutment for engaging the heel-end face of a shoe on said

support, a carriage supporting said abutment and movable lengthwise of the shoe from an initial retracted position to carry the abutment into shoe-engaging position prior to the starting of the power operation of the machine, means for normally limiting such movement of the carriage, means for starting the power operation of the machine, mechanism controlled by said carriage for preventing the starting of the machine by said starting means when the carriage is in its initial retracted position, and a device for retaining said mechanism still in position to prevent the starting of the machine until the carriage has substantially completed its movement to the position determined by said limiting means and for then releasing said mechanism by the action of the carriage.

THEODORE P. COURCHENE.
